UNITED STATES PATENT OFFICE

157,917

BALL PEN POINT

Bertram H. Stewart, New York, N. Y.

Application December 23, 1947, Serial No. 143,307

Term of patent 3½ years

(Cl. D74—1)

To all whom it may concern:

Be it known that I, Bertram H. Stewart, a citizen of the United States of America, residing at New York city, in the county of New York and State of New York, have invented a new, original, and ornamental Design for a Ball Pen Point, of which the following is a specification, reference being had to the accompanying drawing, forming part thereof.

In the drawing:

Fig. 1 is a side elevational view of a ball pen point, showing my new design;

Fig. 2 is a bottom plan view thereof.

I claim:

The ornamental design for a ball pen point, substantially as shown.

BERTRAM H. STEWART.
